UNITED STATES PATENT OFFICE.

EDWIN CALDWELL, OF NEW YORK, N. Y.

DESIGN FOR A RECEPTACLE FOR MATCHES OR OTHER ARTICLES.

SPECIFICATION forming part of Design No. 35,201, dated October 22, 1901.

Application filed July 12, 1901. Serial No. 68,116. Term of patent 7 years.

To all whom it may concern:

Be it known that I, EDWIN CALDWELL, a citizen of the United States, residing at New York, in the county and State of New York, have 5 invented and produced a new and original Design for Receptacles for Matches or other Articles, of which the following is a specification, reference being had to the accompanying drawing, forming part of the same.

10 The figure is a view in perspective showing my new design for a receptacle.

As shown in the drawing, the leading or material feature of my design consists of a cylindrical body A, terminating at one end 15 in a conical end B, at the end of which a hole C is formed. The cover D of the receptacle fits upon the end of the same opposite the

conical end B and is removably secured thereto. Integral with the head D is the handle E, of ring form, as shown. The cover D, where 20 it engages the body of the receptacle, is ornamented with the beading indicated.

Having described my invention, what I claim as new, and desire to secure by Letters Patent, is—

25 The design for a receptacle for matches and other articles as herein shown and described.

In testimony whereof I have signed my name to this specification in the presence of two subscribing witnesses.

EDWIN CALDWELL.
